(57) CLAIM

We claim the ornamental design for ankle protector, as shown and described.

DESCRIPTION

FIG. 1 is a partial right side and rear perspective view of an ankle protector of the present invention;

FIG. 2 is a front view of the ankle protector of FIG. 1;

FIG. 3 is a back view of the ankle protector of FIG. 1;

FIG. 4 is a top view of the ankle protector of FIG. 1;

FIG. 5 is a bottom view of the ankle protector of FIG. 1;

FIG. 6 is a right side view of the ankle protector of FIG. 1; and,

FIG. 7 is a left side view of the ankle protector of FIG. 1.

The broken lines shown in FIG. 1 are included for the purpose of illustration and form no part of the claimed design.
